FOUNTAIN PEN

Filed April 26, 1927

UNITED STATES PATENT OFFICE.

VICTOR SAVIO, OF WASHINGTON, DISTRICT OF COLUMBIA.

FOUNTAIN PEN.

Application filed April 26, 1927. Serial No. 186,751.

This invention relates to an improvement in fountain pens wherein provision is made for utilizing substantially the entire barrel of the pen as an ink reservoir; and providing means to insure against any possible leakage of ink from the barrel when the pen is not in use.

The primary object of the invention is the provision of a fountain pen in which the interior of the barrel is uninterrupted substantially throughout the full length whereby to utilize the full interior of the barrel as an ink reservoir and thus carry a much larger quantity of ink than in other pens of the same size barrel.

A further object of the invention is the provision of means, designed for manual operation, by which the flow of ink to the pen point may be cut off at will, thereby sealing the barrel against possible leakage at this point.

A further object is the provision of a cap which is slidably mounted with respect to the barrel and otherwise inseparable from the barrel, the cap having means by which one end may be closed when the cap is projected into cap-forming position or opened to permit the projection of the pen point therethrough when the pen is designed to be used for writing purposes.

The invention is illustrated in the accompanying drawings, in which:

Figure 1 is an enlarged longitudinal sectional view, partly in elevation, showing the improved fountain pen.

Figure 2 is an enlarged end view of the cap.

Figure 3 is a view in elevation of the pen, showing the cap in dotted outline in position to cover and conceal the pen point and in full lines in position to permit ordinary writing use of the pen.

Figure 4 is a broken section of the barrel and cap, the valve for sealing this end of the barrel being shown in closed position.

The improved pen comprises a barrel 1 which, of course, is of conventional form exteriorly and may be of any appropriate size commensurate with the type of pen contemplated. At one, that is the upper, end of the barrel there is provided a closing section 2 of cap-like form, the joint connection 3 between the barrel and closing section being such as to permit the removal of the closing section when necessary, though ordinarily serving

to connect these parts to prevent their casual separation.

The top or end wall 4 of the closing section is formed with an inwardly extending annular wall 5, which opens through the top 60 of the closing section and is open at the bottom. This wall 5 defines a space inwardly of and annularly divided from the wall of the barrel.

The lower end of the wall 5 is provided 65 with a central bearing sleeve 11 to slidably receive the stem 12 of a valve disk 13, which latter is of a size to completely close the entrance to, that is the lower end of, the space within the wall 5. By suction applied to the 70 upper end of the pen the reservoir is filled.

The opposite or lower end of the barrel is provided with the usual fixed plug 18 having a central passage 19 for the ink. A closure 20 is threaded into the barrel below the plug 18, 75 this closure being formed or provided on its upper side with a valve plug 22 adapted, when the closure is in its upper position, to close the lower end of the channel 19 and prevent the passage of ink therethrough. The closure 20 is provided on its lower surface with a knurled flange 23, the diameter of which is substantially equal to the exterior diameter of the barrel, said closure having a reduced extension 24 to removably receive the pen plug 85 25 with which cooperates the pen point 26.

The closure 20 is hollow and its upper wall is formed with openings 27 beyond the valve plug 22, the pen plug 25 having the usual channel 28 to permit the flow of ink to the pen 90 point. Thus, when the closure 20 has been moved to a point to open the channel 19, ink will readily reach the pen point for ordinary writing purposes. In this position of the closure, as indicated in Figure 1, it will be 95 noted that the flow of ink to the pen point is, following its flow through the channel 19, accumulated in the hollow closure as in a minor reservoir.

The improved pen is designed to be provided with a cap which, when in closing position, acts to protect the pen point and at the same time prevent the clothing from being soiled by the ink accumulated on the pen point when writing. The improved cap, however, is designed to form a more or less permanent part of the barrel and to have a sliding co-operation with the barrel, being otherwise inseparable from the barrel. The cap, therefore, includes a sleeve-like member 29 of an 100 105 110

interior diameter to snugly embrace and fit the exterior of the barrel 1, the wall of the cap having a projection 30 sliding in a groove 31 in the barrel to permit sliding movement of the cap relative to the barrel while preventing separation of the parts.

The outer end of the barrel is provided, through the medium of a removable section 32, with a closure in the form of the conventional diaphragm shutters 33. The shutter formation is of conventional type, permitting the shutters to be opened and closed by rotation of the section 32 as well understood. The cap 29 is further provided with diametrically opposed openings 34 which, when the cap is in extended or closing position, are aligned with the knurled flange 23 of the closure 20, whereby the closure may be manipulated in its threaded connection with the barrel to open or close the channel 19. The pen, of course, may have the usual retaining means arranged at any convenient point and adjacent either end of the pen though preferably as shown arranged adjacent the upper end.

In filling the barrel with ink, the lower or writing end of the pen is first arranged in writing relation, that is, the closure 20 is moved to open the channel 19 and the cap 29 thereupon moved upwardly onto the barrel, the shutter 33 having been opened to permit the end of the cap to pass over and beyond the pen point. Ink is drawn into the barrel of the pen by suction applied at the upper end through any convenient valve..

Following the filling of the pen, if the pen is not desired for immediate use, the cap 29 is moved to its extended or closing position, as indicated in Figure 4, the closure 20 is turned by means of the knurled flange 23, now accessible through the openings 34 in the cap, and the valve plug 22 moved to seal the lower end of the opening 19. The shutter carrier 32 is then operated to close the shutter and both ends of the pen are completely sealed against ink leakage and the pen point end of the pen is completely protected both against

liability to injury and against possibility of soiling the clothing with which this end of the pen may come in contact.

When the pen is to be used for writing, the closure 20 is turned to open the channel 19, the shutter operated to open position and the cap moved rearwardly to expose the pen point, as indicated in Figure 1, following which the pen may be used in the usual manner.

It is, of course, to be understood that the closure 20 may be adjusted relative to the plug 18 to any extent desired to thereby regulate the flow of ink through the passage 19 as may be desired for the particular use of the pen or in accordance with the character of the writing fluid.

What I claim to be new is:

1. A fountain pen having a barrel, a cap slidably mounted on one end of the barrel, the closing end of the cap being adapted to be opened at will, and a sealing closure for the lower end of the barrel operatively accessible through the cap when the latter is in one position.

2. In a fountain pen, a barrel, a cap slidably mounted on one end of the barrel, a closure to seal such end of the barrel, said cap being formed with openings to permit operative access to the closure when the cap is in cap-forming position, and a shutter closure for the end of the cap to permit such end to be opened.

3. In a fountain pen, a barrel, a cap slidably mounted on one end of the barrel, a closure to seal such end of the barrel, said cap being formed with openings to permit operative access to the closure when the cap is in cap-forming position, a shutter closure for the end of the cap to permit such end to be opened, and a pen point plug and pen point carried by the closure and adapted to project through the opened end of the cap when the latter is moved to an inoperative position on the barrel.

In testimony whereof I affix my signature,
VICTOR SAVIO.
